[57] **CLAIM**

The ornamental design for an animal shelter, as shown.

DESCRIPTION

FIG. 1 is a perspective view taken from the top, front and left side of an animal shelter showing my new design;

FIG. 2 is a left side elevational view thereof;

FIG. 3 is a right side elevational view thereof;

FIG. 4 is a rear elevational view thereof;

FIG. 5 is a front elevational view thereof; and
FIG. 6 is a perspective view taken from the top, front and left side thereof, showing the window cover in an alternate position.
